STACK VENT VALVE AND CONTROL THEREFOR

Shirley P. Campbell, Wichita, Kans., assignor to The Coleman Company, Inc., Wichita, Kans., a corporation of Kansas

Application October 18, 1952, Serial No. 315,513

4 Claims. (Cl. 236—45)

This invention relates to a stack vent valve and control therefor. The invention is particularly useful in controlling the inflow of air into the stack of a burner appliance such as, for example, an oil burner, heater, etc.

As the oil is fed to the burner in increased amounts, it is desired to maintain a correspondingly tight draft on the burner so as to bring in more air and thus effect good combustion for the increased fuel fed to the combustion chamber. At the same time, it is desired to have the stack vent control to admit air when the fuel supply is less and it is desired to bring in less air into the combustion chamber. Means have heretofore been provided for providing an interlocking control between the oil feed and the air inlet valve for the stack so as to bleed more air into the stack as less oil is fed to the burner and to tighten the draft by admitting less air to the stack when the quantity of fuel supplied to the burner is increased. I have discovered that this control can be effected through mechanism employed in the stack alone.

An object of the present invention is to provide a structure having the above-described advantages. A further object is to provide a heat-responsive device in the stack controlling the draft upon the burner, the draft being less when less fuel is supplied to the appliance, and greater when more fuel is supplied to the appliance. Yet another object is to provide a highly responsive means located for contact with rising stack gases to change the quantity of air admitted to the stack in response to the heat generated in the combustion chamber. A still further object is to provide in such a structure a pressure-responsive disc which is biased through a thermostat within the stack to provide greater or less resistance to the inflow of air. A still further object is to provide in such apparatus means for deflecting incoming, relatively cool air away from the heat-responsive means. Still a further object is to provide in such a structure a link or arm extension which is substantially non-responsive to the temperature of incoming air while serving as a control arm connecting a heat-responsive bimetallic member within the stack to the air control valve employed. Other specific objects and advantages will appear as the specification proceeds.

The invention is shown in an illustrative embodiment by the accompanying drawing, in which—

Figure 1 is a front view in elevation of a stack conduit equipped with an air inlet and means for controlling a valve for said inlet in accordance with my invention; Fig. 2, a transverse sectional view, the section being taken as indicated at line 2—2 of Fig. 1; Fig. 3, a broken vertical sectional view of the structure shown in Fig. 1; and Fig. 4, a sectional view, the section being taken as indicated at line 4—4 of Fig. 2.

In the illustration given, 10 designates a portion of a stack from an oil burner casing, etc., the stack being provided with a laterally-extending air inlet pipe 11. The stack 10 may be horizontal, vertical, or at any desired angle for leading combustion gases from the casing of the

2

oil burner, etc. In the illustration given, the air inlet pipe 11 is provided on its inner side with a reduced collar 12 extending into the stack or flue pipe 10. The inwardly-extending collar 12 is provided with a support 13 having a flange 14 welded to the member 12, as shown more clearly in Fig. 2.

The outer end of the pipe 11 is turned inwardly to provide a vertical flange 15. A rotatable ring 16 is mounted within the flange 15 and is provided with a flange portion 17 bearing against the outer face of the flange 15 and having also an inwardly-extending collar portion 18.

As shown more clearly in Fig. 4, the flange 15 is provided with three arcuate slots 19. In two of the slots, studs 20 extend through the slot 19 and the front flange 17. The studs extend through washers 21 and are confined there-against by cotter pins 22 extending through the ends of the studs 20. The outer ends of the studs are welded to the outer flange 17. By this means, the ring 16 is rotatably supported upon the air inlet pipe 11 and on the integral flange 15 thereof.

The ring 16 has a central opening within the collar 18, through which air may be admitted into the air-inlet pipe 11 of the stack 10. To control the inlet of air, there is provided within the collar 18 a pressure-responsive disc or valve 23. The pressure-responsive disc is pivoted on an inclined axis extending chordally of the ring so as to be biased to a position normally closing the aperture. The pivot pin 24 has its ends received within bearings 25 mounted at the rear of the ring collar 18. The ring is preferably pressed outwardly at these points to provide relatively straight surfaces 26, as shown more clearly in Fig. 4. In the specific illustration given, the disc 23 is formed of two halves which are secured together at their edges by overlapping one half over the other, and the pin 24 extends through the the valve halves. Since such structure is well known, a detailed description is believed unnecessary. The halves just described are preferably enlarged toward their center. The pressure-responsive disc 23 is preferably provided with a weight 27 on the inner side thereof tending to bias the disc toward closed position. In addition, a small weight 28, consisting of two metal nuts, may be threaded upon a screw passing through the edge portion of the disc 23. Thus both the internal weight 27 and the external weights 28 tend to bias the valve or disc 23 toward closed position when the valve is positioned normally, as illustrated in Fig. 1. Should the ring 23 be rotated clockwise when viewed as shown in Fig. 1, the weights 27 and 28 will be carried toward the bottom of the air-inlet pipe 11, thus decreasing the inclination of the pivot pin 24 and increasing the closing bias on the disc.

I will now describe the heat-responsive or thermostat means which I provide for rotating the ring in a clockwise direction, tending to decrease the inclination of the pin 24 as the temperature in the stack rises. Upon the support 13 which extends rearwardly of the air-inlet member 12, I provide a laterally and upwardly-extending bracket 29, to which is fixed a bimetallic member 30. The bimetallic member 30 is so arranged that upon the heating thereof the member tends to turn laterally and to the left, as viewed in Fig. 2. To the forward end of the bimetallic member or thermostat 30 is secured a blade 31, which extends forwardly and is provided with a laterally-turned end 32, which is secured to a stud 33 extending freely through the bottom slot 19 of flange 15 and which is welded fixedly to the ring flange 17. The blade end 32 is apertured to receive the stud 33 and is secured to the stud by a cotter pin 34, or other suitable means.

With the structure described, the blade 31 is free to move to the left or in a clockwise direction, as viewed

in Fig. 1, and this movement is permitted by the slots 19 receiving the studs 20. Thus, as the bimetallic member 30 is heated and moves laterally, it causes the blade 31 fixed to the ring 16 to rotate the ring in a clockwise direction and thus bring the weighted portion of the disc 23 downwardly toward the bottom of the air inlet 11. This increases the resistance of the pivoted disc or valve against opening and thus maintains a tighter draft within the stack. As a result of the maintenance of the tighter draft, more air is drawn into the burner to meet the demands of the increased fuel, and better combustion results.

While the bimetallic member may be extended to engage the rotatable ring, I prefer to terminate the bimetallic member at a point within the stack and to provide a non-heat-responsive blade 31 of metal or any other suitable material for connecting the member 30 to the rotatable ring 16. I also prefer to equip the blade or support 31 with a deflector or baffle 35 so as to deflect the incoming, relatively cool air away from the bimetallic member 30 so as to make it responsive only to the rising heated gas from the combustion chamber. The deflector 35 may be omitted, if desired, but I prefer to employ it with the non-heat-responsive blade or support 31 as a means for protecting the bimetallic member or thermostat 30 against the temperature influence of the incoming air. I also prefer to add a heat insulating strip between the bimetallic member 30 and the support 13 so as to make the bimetallic member responsive to the stack gas temperature instead of residual heat in support 13.

Operation

In the operation of the device, should no fuel, or very little fuel, be fed to the burner, the position of the ring 16 will be as indicated in Fig. 1, with the pivot pin 24 extending at a relatively high inclination within the ring 16. The higher the inclination of the pivot pin 24, the more easily will the disc 23 open in response to pressure differentials between the exterior and interior of the stack. When the amount of fuel fed to the burner is increased, the rising heated gases from the combustion chamber cause the bimetallic member 30 to move laterally, carrying with it the blade 31, and the ring 16 is rotated in a clockwise direction. This movement of the ring causes the weighted portion of the disc 23 to move downwardly toward the bottom of the air inlet 11. The pivot pin 24 thus moves more toward a horizontal plane and away from an inclined plane, and this action greatly increases the bias of the disc 23 toward closing and against opening. As a result, a tighter draft is maintained on the stack and a greater quantity of air is drawn into the burner for mixture with the increased fuel, thus automatically bringing about better combustion within the combustion chamber. I find that the bimetallic member 30 responds immediately to the increased heat in the combustion gases as the fuel supply is increased, and the air inlet disc is immediately set in a position where it maintains greater resistance against opening and the desired tight draft is thus immediately obtained. On the other hand, as the fuel supply is diminished and there is a cooling of the combustion gases, the thermostat allowed the ring to move back toward the normal position shown in Fig. 1, wherein the valve is freer to open for the admission of greater quantities of air, thus diminishing the draft and reducing the tendency for air to be drawn into the fuel-mixing chamber.

The bimetallic member 30 and blade 31 serve as a resilient arm which moves the ring 16 automatically back to the position shown in Fig. 1 when the stack gases

are cooled, these members serving as a stop or positioning means for the ring 16.

The structure occupies a minimum of space and requires no connection whatever with the oil feed, etc. mechanism, while at the same time automatically supplying a greater draft when the fuel supply is increased. The structure may be modified in many ways, employing different structures, while still utilizing the invention.

While in the foregoing specification I have set forth a specific structure in considerable detail for the purpose of illustrating one embodiment of the invention, it will be understood that such details of structure may be varied widely without departing from the spirit of my invention. I claim:

1. In a damper valve assembly adapted for use in an inlet-equipped stack of a burner appliance, a ring adapted to be rotatably mounted at said inlet and providing an opening therethrough, a valve pivotally carried by said ring for swinging movement between positions opening and closing the ring opening, the pivotal axis of said valve extending chordally of said ring to bias said valve in a normally closed position, and heat-responsive means adapted to be mounted in heat-exchange relation with the products of combustion flowing through said stack and being operatively connected to said ring to rotate the same relative to said inlet in response to changes in the temperature of the products of combustion flowing through said stack and thereby change the chordal position of said pivotal axis and the bias of said valve.

2. In a damper valve assembly adapted for use in the stack of a burner appliance, the stack being provided with an air inlet, a ring adapted to be rotatably mounted in said inlet and being provided with an opening therethrough, a valve carried by said ring for swinging movement about a pivotal axis between positions opening and closing said opening through the ring, the pivotal axis extending chordally of said ring and oriented to bias said valve toward closed position, heat responsive means adapted to be mounted in heat exchange relation with the products of combustion flowing through said stack, and a connecting blade connected with said ring and with said heat responsive means for rotating the ring in response to a temperature change in said heat responsive means, whereby changes in temperature in the products of combustion flowing through said stack effectuate, through said heat responsive means and blade, a rotation of said ring for shifting the position of said pivotal axis and thereby alter the bias on said valve.

3. The assembly of claim 2 in which said blade is arcuate and with said heat responsive means, is arranged to increase the bias on said valve in proportion to an increase in the temperature within said stack and vice versa.

4. The structure of claim 3 in which an air deflector is supported upon said blade in the path of the flow of air through said inlet, whereby said heat responsive means will be influenced solely by the product of combustion flowing through said stack.
